UNITED STATES PATENT OFFICE.

THOMAS I. RANKIN, OF PHILADELPHIA, PENNSYLVANIA, ASSIGNOR TO
ABRAM COX STOVE COMPANY, OF SAME PLACE.

DESIGN FOR A PORTABLE RANGE.

SPECIFICATION forming part of Design No: 35,113, dated September 17, 1901.

Application filed August 27, 1901. Serial No. 73,501. Term of patent 7 years.

To all whom it may concern:

Be it known that I, THOMAS I. RANKIN, a citizen of the United States, residing in Philadelphia, Pennsylvania, have invented and produced a certain new and original Design for a Portable Range, of which the following is a specification.

My design for a portable range is fully illustrated in the accompanying drawing, which represents the range in perspective.

The essential feature of the design is the scroll ornamentation found on the base, the body, and the mantel-shelf of the range.

D is the base of the range, having legs d. Each leg is ornamented with a leaf-scroll, and at the center of the apron d' is a shell-scroll, and extending from this shell-scroll toward the legs are long foliated scrolls, the stem of each scroll crossing the main scroll, as clearly illustrated in the drawing.

D' is the body of the stove, and D² is the oven-door, having a central raised shield, and extending from the bottom of this shield toward each edge of the door are two large scrolls. In the upper corners of the door are small shell-scrolls and extending over the shield are foliated scrolls.

The body of the range is slightly ornamented in keeping with the main ornamentation, and the fire-door D³ is ornamented with a sin-

gle scroll in the form of an inverted letter C, and the hot-water chamber D⁴ is ornamented in keeping with the main ornamentation of the range.

D⁵ is the mantel-shelf, having two shelves 35 d² d³, one mounted above the other. The base of this mantel-shelf is ornamented by a rib, extending the full width of the shelf and terminating at each end in scroll ornamentation, and between the shelf and the rib are ornamental scrolls. The space between the shelves d² and d³ is ornamented by a central shield formed by ornamental C-scrolls, and at each end are other C-scrolls connected to the central ornamental support by cross-scrolls. The 40 back plate of the upper shelf is ornamented by a central shell-scroll, from which extends long foliated scrolls.

I claim—

The design for a portable range as herein 50 described and as illustrated in the accompanying drawing.

In testimony whereof I have signed my name to this specification in the presence of two subscribing witnesses.

THOMAS I. RANKIN.
